UNITED STATES PATENT OFFICE.

CHARLES T. MARTIN, OF CHICAGO, ILLINOIS, ASSIGNOR TO THE CONSUMERS GAS SAVING AND INSPECTION COMPANY, OF SAME PLACE.

DESIGN FOR A NURSERY-BURNER.

SPECIFICATION forming part of Design No. 18,274, dated April 24, 1888.

Application filed March 14, 1888. Serial No. 267,159. Term of patent 7 years.

To all whom it may concern:

Be it known that I, CHARLES T. MARTIN, a citizen of the United States, residing at Chicago, in the county of Cook and State of Illinois, have invented and produced an original Design for Nursery-Burners, of which the following is a specification, reference being had to the accompanying drawing, forming part thereof, such drawing being a perspective view of my newly-designed nursery-burner.

As represented in the drawing, the burner is composed of a bell-shaped base or body, above which are arranged two circular rims of a larger diameter than the top of the bell-shaped base. Such rims are arranged some distance apart and united or connected together by a perforated band, forming a contracted neck between the rims. In a plane slightly above the upper one of said rims is arranged a star-shaped skeleton frame or top.

The leading feature of my design is the star-shaped skeleton frame or top superimposed above a circular bell-shaped base or body.

Having fully described my invention, what I desire to claim and secure by Letters Patent is—

The design for a nursery-burner herein shown and described, comprising a superimposed star-shaped skeleton frame, circular rims, contracted perforate neck, and bell-shaped base or body.

In testimony whereof witness my hand this 25th day of February, 1888.

CHARLES T. MARTIN.

In presence of—

A. J. CONNOR,
ROBERT BURNS.
